(57) **CLAIM**

The ornamental design for blade setter for electric clippers, as shown and described.

DESCRIPTION

FIG. 1 is a perspective view of a blade setter for electric clippers;

FIG. 2 is a front elevation view of the invention;
FIG. 3 is a right side view of the invention, the left side view being a mirror image;

FIG. 4 is a rear elevation view of the invention; and

FIG. 5 is a top plan view of the invention;

FIG. 6 is a bottom plan view of the invention; and,

FIG. 7 is a front elevation view of the invention in use.
The broken lines in the drawings represent unclaimed environmental subject matter and form no part of the claim.**1 Claim, 2 Drawing Sheets**(56)
